UNITED STATES PATENT OFFICE.

JAMES B. CRANE, OF NEWNAN, GEORGIA, ASSIGNOR OF ONE-HALF TO J. L. BARRETT, OF SAME PLACE.

OIL-FILTER.

SPECIFICATION forming part of Letters Patent No. 478,251, dated July 5, 1892.

Application filed December 24, 1891. Serial No. 416,070. (No model.)

To all whom it may concern:

Be it known that I, JAMES B. CRANE, a citizen of the United States, residing at Newnan, in the county of Coweta and State of Georgia, 5 have invented a new and useful Oil-Filter, of which the following is a specification.

This invention relates to the treatment of oils, and more especially to the refining or cleansing thereof by filtering it through cotton waste and sawdust and then passing it 10 through water or some other liquid of greater specific gravity than the oil; and the object of the same is to produce an improved filter or apparatus for doing this work in a very 15 rapid and economical manner.

To this end the invention consists in the construction hereinafter more fully described and claimed, and as illustrated on the accompanying sheet of drawings, in which—

20 Figure 1 is a perspective view of my refining apparatus complete. Fig. 2 is a plan view thereof, with the cover raised and the perforated top to the filter-box partially removed. Fig. 3 is a transverse vertical section.

25 Referring to the said drawings, 1 designates the body of this device, which is preferably cylindrical, as shown, having handles 2 and having a cover consisting of a stationary half 3 and a movable half 4, hinged at 5 to the stationary half and having a knob or handle 6.

30 7 is an oil-cock, 8 a water-cock, and 9 an exhaust-cock, all communicating with the interior of the body and at proper heights, as shown.

35 10 is the water-supply tube, which passes through the stationary portion of the cover, wherein it is secured, as at 11, extends nearly to the bottom of the body, where it is open, as at 12, and has its upper end 13 enlarged or funnel-shaped and preferably closed by a cap 14.

40 20 is the oil-feed tube, which is located within the body and supported by the bracket 21. At its lower end this tube bends forwardly, as at 22, and opens into the bottom of a filter-box 23, containing cotton waste 24 or other good filtering material. The top of this box is open and has side grooves 25, and 26' is a 45 perforated top plate sliding in said grooves to prevent the escape of the filtering material.

50 26 is the oil-supply tube, which passes through a collar 27 in the stationary portion

of the cover and is removably inserted in the upper end of the oil-feed tube 20, while the upper end of the oil-supply tube is enlarged, as at 28, being of cylindrical shape and open 55 at its upper end.

30 is a rod having a handle 31 at its upper end and an enlarged head 32 at its lower end, and on this rod are mounted several perforated disks 33, between which is located cotton or other waste 34. In the upper end of the oil-feed tube 20 is preferably placed a wad 35 of cotton waste, above which may be located sawdust 36 or other good filtering material. 65

In operation the cocks are closed, water is poured in through the tube 10 to about the level shown in Fig. 3 and the cap 14 put on, and the box 23 and enlarged upper end 28 of the oil-supply tube are provided with their 70 proper filtering materials. Crude oil is then poured into the oil-supply tube onto the uppermost disk 33, through which it passes and percolates through the several filtering materials, being assisted, if necessary, by the operator, who reciprocates the rod 30 by its handle, and the oil passes down the tube 20, up into and through the filter-box 23, out the perforated top plate 26' thereof, and rises through the water to the water-level, on which it floats, 75 as will be understood. The several filterings to which the oil is thus subjected will thoroughly remove therefrom the lighter particles and impurities, which would otherwise float on the water, and the latter removes from the 80 oil the heavier particles, which of course automatically separate from the oil globules or drops as they rise through the water, the particles sinking to the bottom of the water. The oil can be drawn off through the oil-cock 7 85 from time to time and the water through the water-cock 8, and when desired the entire device can be emptied and cleansed of its sediment through the exhaust-cock 9. The filter is preferably of galvanized iron or other non-corrosive metal, with the trimmings—such as 90 the cocks, handles, and knob—of any desired material, and the sizes, proportions, and shapes of parts are not essential to the successful operation of the device. 100

What is claimed as new is—

1. In an oil-filter, the combination of a cy-

lindrical body, a cover comprising a stationary and a hinged half, cocks in said body, a water-supply tube secured through said stationary half and leading nearly to the bottom of the body, its upper end being funnel-shaped, a cap for closing said end, a filter-box within the body below the water-level, a tube leading from the bottom of the filter-box up through the cover of the body and having an enlarged cylindrical upper end, a rod having a handle at its upper end and an enlarged head at its lower end, perforated disks mounted on said rod and of a size to move within said cylindrical upper end, and filtering material between said disks and within said upper end, as and for the purpose hereinbefore set forth.

5 2. In an oil-filter, the combination, with the body and means for partially filling it with

10 15

water, of a filter-box within the body below the water-level, a tube leading from the bottom of the filter-box up through the cover of the body and having an enlarged cylindrical upper end, a rod having a handle at its upper end and an enlarged head at its lower end, perforated disks mounted on said rod and of a size to move within said cylindrical upper end, and filtering material between said disks and within said upper end, as and for the purpose hereinbefore set forth.

In testimony that I claim the foregoing as 30 my own I have hereto affixed my signature in the presence of two witnesses.

JAMES B. CRANE.
